(57) **CLAIM**

The ornamental design for a handbag, as shown and
described.

DESCRIPTION

FIG. 1 is a bottom plan view of my new design, with certain
stitching and certain hardware shown in dashed line for
illustrative purposes only and forming no part of the claimed
design;

FIG. 2 is a front elevation view thereof;

FIG. 3 is a right side elevation view thereof, the left side
elevation view being a mirror image thereof;

FIG. 4 is a top plan view thereof; and,

FIG. 5 is a rear elevation view thereof.
